UNITED STATES PATENT OFFICE

2,488,687

CONTROLLABLE PITCH PROPELLER

Martin M. Senenich, Lancaster, Pa., assignor to
 Senenich Corporation, Lancaster, Pa., a corporation of Pennsylvania

Application February 20, 1946, Serial No. 648,945

2 Claims. (Cl. 170—160.32)

1

This invention relates to controllable pitch propellers and has primarily in mind the so-called hydraulic control type.

The primary objects of this invention are: to provide means for increasing, stepping up or multiplying the power of the thrust received from a movable member, such as a cross-head or spider, to the point where it is delivered to the blades to force them through opposed partially rotary movements to change their pitch, said cross-head or spider being moved by any suitable means, such as fluid under the pressure of an engine low pressure lubrication system; and, to provide reversely operating levers disposed in the propeller hub outside of a sliding sleeve reciprocated in said hub under the control of suitable actuating means and the thrust of the propeller blades, and functioning as the means above referred to.

In practice it is found that the lubricating oil pressure employed in aircraft engines varies widely according to the make of the engine, in some the pressure running to eighty (80) pounds and over and in others being as low as around thirty (30) or thirty-five (35) pounds or less. Where the pressure runs to 80 pounds or even considerably less there is no need to step it up by levers or other interposed means serving the function mentioned in the preceding paragraph, but where the pressure is as low as around 35 to 40 pounds it is not sufficient to rotate the blades about their axes to the required pitch positions and with the necessary certainty and speed in opposition to the centrifugal, aerodynamic and other forces to which said blades are subject, and this invention finds its primary field of use in controllable pitch propellers driven by engines having low pressure lubricating oil systems powering the so-called hydraulic control systems of said propellers.

As of the present time it is understood that close to ninety per cent (90%) of all aircraft engines made and offered for sale in the United States of 250 horsepower or less, such as would be used for privately owned personal planes, and running in volume to a bit more than 35,000 such engines per year, are the product of a company employing a low pressure lubricating oil system with oil pressure around 35 pounds, so that my present invention for stepping up such pressure as it is eventually applied to the blades to change their pitch has a substantial field of application as of the present time.

In the accompanying drawings:

Figure 1 represents a view partly in side eleva-

tion and partly in section of the hub and root portions of the blades of a dual blade propeller embodying my invention and as secured to the engine shaft S;

5 Figure 2, a view partly in front elevation and partly in section thereof;

Figure 3, a sectional view on the line 3—3 of Fig. 2, looking in the direction of the arrows;

10 Figure 4, a section in the plane of line 4—4 of Fig. 5;

Figure 5, an inner side elevation of one of the levers 40 as engaged by one of the pins or fingers 22 of the spider, cross-head or traveler 21 and engaging the compensating guide block 26 receiving in its bore the corresponding pitch adjusting stud or lug 25 of one of the blades 7;

Figure 6, an end plan view of one of the levers 40;

20 Figure 7, an edge elevation thereof;

Figure 8, an outer side elevation thereof;

Figure 9, a side elevation of the spider or traveler 21;

Figure 10, a plan view of one of the compensating blocks 26; and

25 Figure 11, an edge elevation thereof.

The drawings illustrate a two blade or dual blade embodiment of my invention in a so-called hydraulic control type of controllable pitch propellers, though of course this invention is not restricted to a dual blade propeller, nor, considered in its broader aspects, is it necessarily limited to use with propellers of the so-called hydraulic control type.

A propeller assembly in which the present invention is embodied and employing fluid under pressure as its control actuating medium may be said to be comprised of four main groups of elements as follows: the hub per se; the blades 7 with their roots, ferrules, end caps, split lock rings, bearings, races, retaining collars or nuts, locking means for the latter, all in general of prior known construction and design, their pitch bosses or pins and their weights where the latter are employed; the hydraulic or fluid pressure control mechanism; and the power boosting means interposed between the spider or cross-head 21 and the pitch bosses or pins 25 of the blades.

Referring now in detail to the drawings, S designates the engine shaft having a flange F to which is bolted the flange 4 of the propeller hub by means of bolts and nuts 14 and which is provided with a boss B fitting in the large diameter rear portion of the rear centering support, guide-bush or bearing 3. The shaft S is

hollow or formed with an oil or hydraulic fluid duct or bore O , there being provided any usual conventional means, not shown, for supplying oil or hydraulic fluid from the usual engine lubrication system and at the pressure of said system through the bore O of said shaft S to the hydraulic system and for shutting off said supply at will, and there also being provided usual conventional means, not shown, for draining oil from said hydraulic system through said bore O of said shaft S into the crank case of the engine when the supply of fluid under pressure through the shaft S has been cut off, the arrangement being such that when the supply duct is open the drain duct will be closed and when the drain duct is open the supply duct will be closed, all in accordance with well known and usual practice in the art.

The hub body 1 is formed with a central bore or opening extending at right angles to the axis of said body and a centering support or guide-bush or bearing 2 is brazed, welded or otherwise suitably secured or formed in the front wall of said opening in axial alignment with a similar bush or bearing 3 similarly secured or formed in the rear wall of said opening, and said bushes or bearings 2 and 3 may be provided with suitable bearing linings as illustrated, in any suitable manner, and the propeller mounting flange 4 is secured to the rear end of the bush or bearing 3 and to the adjacent portions of the body 1 at all points about the bush or bearing 3 by welding or brazing or in any other suitable known manner.

The rear centering support or guide-bush or bearing 3 is preferably formed with a radial inner rearwardly presented shoulder 5 , that portion of bush 3 in front of said shoulder 5 being of smaller diameter than that to the rear of said shoulder 5 , and snugly receiving, supporting and guiding the reduced rear end portion 16 of the sleeve 20 , the larger diameter portion of said bush 3 to the rear of the shoulder 5 receiving and holding in proper centered position the engine shaft boss B and an abutment plate or disc 33 bearing against the shoulder 5 and held in place by the pressure of boss B , a suitable fluid sealing gasket 35 of any suitable preferably compressible material being interposed between the annular end face of boss B and the radially outer portion of the opposed rear face of disc 33 .

A pitch or adjusting lug or stud 25 is secured to the root end of each blade 7 to extend inwardly of the hub axially of the blade at a point remote from the axis of the blade.

Weights 11 may be secured to the respective blades 7 in such angular positions as to tend to turn said blades to, and maintain them in, their high pitch position during the rotation of the propeller unless and until counteracted by the positive action of the hydraulic mechanism acting to forcibly turn the blades 7 to, and hold them in, their low pitch positions while the oil or other fluid is supplied under pressure, or maintained under pressure, to said hydraulic mechanism. To this end each weight 11 is connected to a band 12 which encircles the stem or ferrule of a corresponding blade 7 and is provided with a nut and bolt 13 or other suitable means for drawing said band 12 into tight binding and locking engagement with said stem or ferrule to hold the said weight 11 in any selected position of angular adjustment thereon against movement relative thereto.

The sleeve 20 is preferably integral with the enlarged cylindrical cup or cylinder 37 at its for-

ward end, and is formed with three external cylindrical portions, being an extreme rear end reduced diameter bearing portion 16 making a snug sliding fit in the reduced diameter front portion of the rear bush or bearing 3 for reciprocatory movement therein; an intermediate externally screw-threaded portion 17 , and a large diameter bearing portion 18 making a snug sliding fit in the front bush or bearing 2 for reciprocatory movement therein, and is formed in said front portion with a plurality of preferably equi-distantly spaced locking slots 19 preferably arranged in a circular series and preferably extending entirely through the wall of sleeve 20 .

The threads of the externally screw-threaded portion 17 engage the internally screw-threaded traveler, spider or cross-head 21 and the internally screw-threaded adjusting nut 27 .

By holding the adjusting nut 27 against turning and turning the sleeve 20 in the spider or cross head 21 and in adjusting nut 27 , said spider 21 and nut 27 may be adjusted to different positions axially of the sleeve 20 or by releasing the nut 27 to turn with sleeve 20 and turning the sleeve 20 in spider 21 the position of the latter may be adjusted axially of the sleeve 20 and also with relation to nut 27 , or by holding sleeve 20 against rotation and turning the nut 27 thereon the latter may be adjusted axially of the sleeve 20 with relation to spider 21 and the abutment face 27 .

A removable locking stud or pin 15 screwed into a suitable screw-threaded hole in the wall of bush or bearing 2 and having a preferably smooth tip to fit in any one of said slots 19 serves to lock said sleeve 20 against any appreciable rotary or partially rotary movement.

Access to the interior of the hub may be had by a suitable tool introduced through a screw-threaded hole normally closed by a plug 29 for manipulating the adjusting nut 27 as above mentioned.

The traveler, spider or cross-head 21 is formed with a pair of diametrically opposite arms, fingers or pins 22 extending laterally outwardly of the hub in opposite directions and these fingers, or pins 22 engage with other parts of the assemblage and prevent the rotation of the spider or cross-head 21 with the sleeve 20 in the assembled relation of the parts.

A thrust or piston rod 30 having a rear end nipple snugly slidably removably fitting in and preferably through the central opening of the abutment plate or disc 33 extends lengthwise through the sleeve 20 and nearly to the cylinder head or front or cover plate 37 and has an externally screw-threaded nipple extending through a dished form piston 34 and a flexible diaphragm of any suitable material, such for instance as molded neoprene. A nut 36 turning on the extreme front end portion of said threaded front end nipple extending forward beyond said diaphragm 38 serves to tightly clamp said piston 34 and diaphragm 38 between said nut 36 and an annular flange or shoulder 32 integral with or rigidly secured to the forward end portion of said thrust or piston rod 30 . The rear end portion of the thrust or piston rod 30 is formed or provided with a preferably annular shoulder or flange 31 integral with or rigidly secured to said rod 30 which exerts a thrust against the abutment plate or disc 33 .

The outer peripheral portion of the diaphragm is clamped with a fluid tight seal between the front edge of the cylinder 37 and the cylinder head or cover plate 37 which is preferably formed

with an internally screw-threaded rearwardly presented flange engaging cooperating external screw-threads on the cylinder 37, such construction resulting in an expansible fluid tight chamber 39 between the diaphragm 38 and the cylinder head or cover plate 37', the joint between the diaphragm 38 and the thrust or piston rod 30 being similarly sealed fluid tight.

Admission of oil or hydraulic fluid under pressure into this chamber 39 through the hollow shaft S and thrust or piston rod 30 will exert a thrust on the abutment plate 33 and the cylinder head or cover plate 37', causing the latter to move forward together with the cylinder 37 its sleeve 20 and the spider or cross-head 21 carried by said sleeve, and release of such fluid from said chamber 39 will permit the cylinder 37, with its head 37', sleeve 20 and the cross-head or spider 21 carried by the latter to be moved rearward by the partial rotary movement of the blades 7 about their axes when released from the influence of the hydraulic fluid.

All parts thus far described are shown and described in detail in the Sensenich and Uhrich patent application, Ser. No. 596,442, filed May 29, 1945 for Controllable pitch propellers and are not of my invention except in so far as they are modified and form part of the combination of my present invention, which starts with the disclosure of said Sensenich and Uhrich application as a foundation and constitutes an improvement thereon primarily to provide a simple controlled pitch propeller of the so-called hydraulic type particularly adapted for operation by the oil of the lubrication system of engines employing low pressures, such for instance as of around 30 to 40 pounds pressure, though of course the degree of pressure may vary, though the higher the degree of pressure the less the need for means for stepping up the power of the hydraulic fluid as eventually applied to change the pitch of the blades.

The power boosting means comprises levers 40 respectively to connect the traveler, spider or cross-head 21 to the roots of the respective blades 7, translating the linear movement of the cross-head 21 into rotary movement as applied to said blades, and increasing the power of the thrust of the cross-head 21 as actually applied to the blades 7.

Said levers 40 are respectively disposed in the hub body 1 exteriorly of and on opposite sides of the sleeve 21 and are respectively pivotally mounted on pivot pins 41 disposed on opposite sides axially of the body 1 of the axis of sleeve 21.

The pivot pins 41 are secured to or in the body 1 of the hub in any suitable manner, as by being driven with a tight drive fit into suitable holes or bores made through the wall of said body 1 to receive them and by being made of a very slightly larger diameter, say one ten-thousandth of an inch, than the internal diameter of the holes into which they respectively are to be pressed or driven.

A spacing and reinforcing washer 42 preferably also having an opening of the same diameter as the hole or bore in which its pin 41 is to be forced is applied to each pin 41 and in assembled relation is in engagement with the wall of the hub adjacent the pin as pressed or forced into place and said washer 42 is preferably brazed to the body 1.

As thus mounted each lever 40 will have a long arm and a short arm, the long arm being pref-

erably substantially twice as long as the short arm.

The long arm of each lever 40 has its free end notched or bifurcated as at 44 to receive the corresponding finger or pin 22 of the traveler, spider or cross-head 21, and the free end of the short arm of each lever 40 is formed with a shallower but wider slot 43 to slidably receive an adjusting and wear compensating thrust block 26 which has an off-center bore receiving the pitch boss, lug or pin 25 of the immediately adjacent root of the adjacent blade 1.

Each of the four outer edge faces of each of the square thrust blocks 26 will preferably be convexly radiussed or rounded to properly cooperate with the walls of their corresponding slots 43 in the free ends of the short arms of the levers 40 as the same swing about the axes of their respective pivot pins 41, and preferably will be insertable in their respective slots 43 in any one of four positions according as may be necessary to obtain the proper adjustment either in the original assembly or to compensate for wear.

This thrust block 26 per se, and the pitch boss, lug or pin 25 per se, and the details for connecting said pitch boss or pin 25 to its blade root were known prior to my present invention, being shown and described in the above referred to Sensenich and Uhrich patent application.

With the parts constructed, arranged and combined as above described, assuming the blades 7 are provided with the weights 11 and normally are in their high pitch positions, the levers 40 being in their neutral positions perpendicular to the axis of sleeve 20, and that it is desired to shift the blades 7 to their low pitch positions for taking off or climbing, admission of oil under pressure to the chamber 39 will force the cylinder head 37' with cylinder 37, sleeve 20 and traveler, spider or cross-head 21 forward and through the engagement of the fingers or pins 22 with the walls of slots 44 in the free ends of the long arms of the levers 40 will swing said levers 40 about the axes of their respective pivots 41 and by their double length substantially doubling the force of the thrust of the hydraulic fluid received by the spider or cross-head 21 as the same is applied to the pitch bosses or lugs 25 by the short arms of the respective levers 40.

When the take-off or climb has been completed and it is desired to permit the blades to assume their normal high pitch positions for straight away flying, the supply of fluid under pressure to chamber 39 is cut off and the drain therefrom to the engine crank case is opened and the blades 7 being released from the hydraulic control means will be turned to high pitch positions by the centrifugal and other forces and influences, including the weights 11 to which they are subjected, and in so doing will swing the levers 40 back to their initial neutral positions and said levers will simultaneously force the sleeve 20 with its connected cylinder 37 and cylinder head or cover plate 37' in the reverse axial direction back to their initial positions, the reverse movement of the cylinder head or cover plate 37' as it progresses expelling the oil from the chamber 39 into the engine crank case.

Of course the embodiment of the invention illustrated, while presently preferred, is merely one of many possible embodiments, and that simply as applied to a dual or two blade hydraulic control type of propeller, the construction and arrangement of parts would be varied appropriately

in its application to a propeller having more than two blades or to a propeller employing a different power source for controlling the pitch movements of the blades; and the details of the power multiplying or increasing couple or connecting means interposed between the spider or cross-head and the blades may be varied in a great many ways, various forms of levers may be used, or levers as such may be entirely dispensed from, it sufficing so long as there is provided some power increasing or multiplying means capable of increasing the power received by the spider or cross-head 21 as applied to the blades, sufficiently to function properly in shifting the pitch of the blades 17 and holding them as long as required or desired in the newly adjusted pitch position by comparatively low power means.

I claim:

1. A controllable pitch propeller comprising a hub to be secured to an engine shaft and to have its interior in communication with means for supplying fluid under pressure thereto and means for draining fluid therefrom, propeller blades mounted in said hub, pitch pins respectively extending from said blades, a sleeve mounted for reciprocation in said hub and having an externally screw-threaded portion, hydraulic mechanism for forcing said sleeve in one direction axially thereof against the reverse thrust of said blades, releasable means for locking said sleeve against rotary movement relative to said hub while permitting its axial movement therein, a spider having screw-thread engagement with the screw-threaded portion of said sleeve, and an adjustable pitch movement limiting nut having screw-thread engagement with the screw-threaded portion of said sleeve and normally turning therewith and limiting the extent of the power thrust movement thereof by engaging a relatively fixed part carried by the hub, said spider and nut being adjustable to different positions axially of said sleeve either simultaneously in the same axial direction and to the same degree or separately and relatively to each other, in combination with levers pivotally mounted in said hub radially outside of said sleeve to swing about

axes respectively fixed relative to said hub and respectively having long arm portions and short arm portions, the respective long arm portions of said levers respectively engaging said spider to be thrust thereby in one axial direction and to exert a thrust in the reverse direction upon said spider, and the respective short arms of said levers respectively engaging the respective pitch pins of the respective blades to thrust them in one direction under the thrust of said spider and to receive thrust from them in the reverse direction.

2. A controllable pitch propeller comprising a hub to be secured to an engine shaft and to have its interior in communication with means for supplying fluid under pressure thereto and means for draining fluid therefrom, propeller blades mounted in said hub, pitch pins respectively extending from said blades, a sleeve mounted for reciprocation in said hub, and a spider carried in fixed position by said sleeve, in combination with levers pivotally mounted in said hub radially outside of said sleeve to swing about axes respectively fixed relative to said hub and respectively having long arm portions and short arm portions, the respective long arm portions of said levers respectively engaging said spider to be thrust thereby in one axial direction and to exert a thrust in the reverse direction upon said spider, and the respective short arms of said levers respectively engaging the respective pitch pins of the respective blades to thrust them in one direction under the thrust of said spider and to receive a thrust from them in the reverse direction.
